BROADBAND LOOP ANTENNA

Sidney Frankel, Bergensfield, N. J., assignor to
 International Standard Electric Corporation,
 New York, N. Y., a corporation of Delaware

Application July 29, 1949, Serial No. 107,406

7 Claims. (Cl. 250--33)

1

This invention relates to antennae and is particularly directed to improvements in loop antennae having high radiation conductance and broadband characteristics in the ultrahigh frequency range. The antennae of this invention are adapted for nondirectional broadcasting.

It is desirable in ultrahigh frequency broadcasting to efficiently load the generator of the energy to be radiated as well as to prevent frequency selectivity of the radiator system over a wide range of frequencies. Unfortunately, both these conditions have not heretofore been realized in one antenna structure. While the reactive components of the load may be tuned out by the addition of reactances of compensating signs, the resulting Q is high and broadband characteristics are sacrificed.

An object of this invention is an antenna that has both broadband characteristics and high radiation conductance.

A more specific object of this invention is a loop-type antenna that is nondirectional.

A still more specific object of this invention is a nondirectional loop antenna of simple, rugged, and easy-to-make construction.

The objects of this invention are realized by a longitudinally slotted sheet metal cylinder with the conductors of a coaxial transmission line extending into one end and through the cylinder. The edges of the cylinder slot are connected, respectively, with the inner and outer conductors and the annular space between the cylinder and outer conductor constitutes a tunable cavity resonator electrically in parallel with the impedance at the slot.

The above-mentioned and other features and objects of this invention and the manner of attaining them will become apparent and the invention itself will be best understood by reference to the following description of preferred embodiments of the invention taken in conjunction with the accompanying drawing, wherein:

Fig. 1 is a perspective view, partly in section, of a single slot antenna structure of this invention;

Fig. 2 is an end view of the structure of Fig. 1; Fig. 2a is a circuit diagram of the principal electrical parts of the structure of Fig. 2; and

Figs. 3 and 4 are end views of multi-cavity modifications of the antenna of Fig. 1.

The antenna of this invention comprises a symmetrical smooth sheet metal cylinder 1 closed at one end with plate 2 having a longitudinal slot 4 extending from end-to-end. A coaxial transmission line is telescoped into said cylinder through one end, inner conductor 5 and outer conductor

2

6 extending through to the end plate. The high frequency voltage between the inner and outer conductors are applied, respectively, to opposite edges of the slot 4 by radially disposed vanes 7 and 8. The edges of vane 7 are joined in continuous line contact to one edge of the cylinder slot and the outer conductor, while the vane 8 extends centrally through a window in the outer conductor 6 and joins the inner conductor to the other edge of the slot. Openings 9 and 10 between the vane 8 and either side of the window may be predetermined as hereinafter described.

A tunable cavity resonator 11 is connected across the transmission line and in electrical parallel with the antenna load presented at the slot 4. The input opening 10 to the cavity resonator admits an exciting field to the cavity resonator, the length of the cavity being measured by the mean circumferential distance from the opening to an adjustable short circuiting partition 12.

An equivalent high frequency circuit for the cylinder and coaxial line may be drawn, as shown in Fig. 2a. It has been found that the impedance Z of the cavity resonator presented at the input opening 10 to the transmission line may be adjusted to capacitive or inductive value for any applied frequency merely by tuning the cavity resonator to resonance at a frequency above or below the applied frequency. Such tuning is most conveniently effected by moving the partition 12 toward or away from the opening 10.

It is found further, that the impedance presented by the outside slot 4 to the transmission line is capacitive C and resistive R only, the absence of inductive impedance being expected when it is recalled the antenna cylinder is closed at one end and can link with no electromagnetic lines of force. That is, radio frequency current flows radially over the opposed faces of the vanes 7 and 8 and from one edge of the slot 7 to the other along the outer surface of the cylinder, and since the cylinder sides and end are impervious to such currents there can be no self induced voltages. Now, according to an important feature of this invention, the capacitive reactance of the loop circuit may be precisely balanced out by an equal and parallel inductive reactance that can be obtained at the opening 10 to the cavity by adjustment of the tuning partition 12. The load thus presented to the transmission line can be made entirely resistive and because the conductor and dielectric losses are small the largest portion of the resistance is attributable to radiation. For the smaller range of spacings between 7 and 8, the shunt capacitance varies in

45
 50
 55

versely with the spacing. The efficiency of radiation of this antenna is high.

More uniform radiation, increased radiation conductance, and still broader band characteristics may be obtained by employing a larger number of slots. In Fig. 3, for example, four equally spaced slots 13, 14, 15 and 16 are shown, although a larger or smaller number may be used if desired. As in Fig. 1 the two edges of each slot is joined by vanes 7 and 8 to the outer and inner conductors, respectively, of the transmission line. Each of the wider vanes 8 extends through, without contacting, the windows in the outer conductor so that the fields within the line are open to both the antenna slots 13-16 and to cavity resonators 11. Each resonator is tuned by the short-circuit partition 12.

In case the number of segments of the antenna cylinder, for the operating frequency, is large, and the circumferential distance between slots is too small to accommodate the full length of the cavity resonators, the resonators may be folded as shown in Fig. 4. By the placement of sheet metal walls a cavity of desired length may be coiled within the limits of each segment. It is suggested in Fig. 4 that the vanes and curved wall portions of each segment be fashioned from single pieces of sheet metal, copper being one metal that has good conductivity and is easily bent.

While there has been described above the principles of this invention in connection with specific apparatus, it is to be clearly understood that this description is made only by way of example and not as a limitation to the scope of this invention.

What is claimed is:

1. An antenna comprising a coaxial transmission line, a longitudinally slotted cylinder encircling and coaxial with the conductors of said transmission line, the outer conductor of said line having a slot in registry and coextensive with the slot of said cylinder, the edges of the cylinder defining the slot being joined throughout the length of the cylinder slot to the inner conductor and outer conductor, respectively, of said transmission line.

2. An antenna system comprising a sheet metal cylinder and concentric conductors of a transmission line, said cylinder and conductors being coaxial and being provided with registering longitudinal slots in the cylinder and outer conductor, a first radial vane joining one edge of the cylinder defining the slot therein to one edge of the outer conductor defining the slot therein, a second radial vane extending through the outer conductor slot and joining the other edge of the cylinder defining the slot therein to the inner conductor.

3. An antenna system as defined in claim 2 in which the annular space between said cylinder and outer conductor is in communication with

the space inside said outer conductor, and a movable vane in said annular space to adjust the dimensions thereof.

4. The combination comprising a transmission line with coaxial conductors adapted to conduct high frequency energy, a loop antenna comprising a sheet metal cylinder telescoped over and concentric with the outer conductor of said line and provided with at least one longitudinal slot, the outer conductor of said line being slotted over its length within said cylinder, means coupling said transmission line and said antenna through said slots for impressing high frequency voltage across the edges of said slot from the electric field within said transmission line and for exciting the annular space between the cylinder and said outer conductor of the line

5. The combination of a loop antenna and transmission line, said line comprising coaxial conductors provided with windows in the outer conductor and said antenna comprising a metal cylinder telescoped over said line and provided with a plurality of longitudinal slots in said cylinder registering and coextensive with said windows in the outer conductor of said line, a vane extending radially from the inner conductor centrally through each of said windows to one edge of said cylinder defining each of said slots, and vanes joining the opposite edge of said cylinder defining each slot to one edge in said outer conductor defining each window.

6. The combination as defined in claim 5 in which the annular space bounded by said cylinder, said outer conductor and said vanes are in communication with the interior of said outer conductor and are dimensioned to resonate near the operating frequency.

7. A broadband ultrahigh frequency antenna comprising three spaced coaxial cylinders, the outer cylinder being provided with a slot, the edges of said cylinder defining the slot being electrically connected to the inner cylinders, the first annular space between the outer two cylinders being provided with a communicating opening into the second space between the inner two cylinders, and a radial short circuiting vane in said first space and adjustable in a circumferential direction along said first space.
